UNITED STATES PATENT OFFICE.

JAMES C. WORKMAN, OF LAKEWOOD, OHIO, ASSIGNOR TO THE AMERICAN SHIP BUILDING COMPANY, OF CLEVELAND, OHIO, A CORPORATION OF NEW JERSEY.

REMOVABLE COVERING FOR BOILERS.

1,363,173.

Specification of Letters Patent. Patented Dec. 21, 1920.

Application filed September 19, 1916, Serial No. 121,034. Renewed May 18, 1917. Serial No. 169,570.

To all whom it may concern:

Be it known that I, JAMES C. WORKMAN, a citizen of the United States, and a resident of Lakewood, county of Cuyahoga and State of Ohio, have invented a new and useful Improvement in Removable Coverings for Boilers, of which the following is a specification, the principle of the invention being herein explained and the best mode 10 in which I have contemplated applying that principle, so as to distinguish it from other inventions.

The present invention, relating as indicated to removable boiler covering, deals 15 more particularly with a sectional covering or coating for boilers used on ships where, under the present inspection laws, it is necessary to provide some means for conveniently removing the covering around the 20 ends of the boiler so that the inspection may be made of the rivets at the joint between the end and sides of the boiler. It is only necessary that such a covering be used on a portion of the boiler, although if it is desired the entire boiler may be covered with 25 a removable or sectional covering constructed in accordance with the principles of the present invention. To the accomplishment of the foregoing and related ends, said invention, then, consists, of the means herein- 30 after fully described and particularly pointed out in the claim.

The annexed drawing and the following description set forth in detail certain mechanism embodying the invention, such disclosed means constituting, however, but one of various mechanical forms in which the principle of the invention may be used.

In said annexed drawing:-

40 Figure 1 is a perspective view showing the outer end of a boiler provided with my improved covering; Fig. 2 is a bottom plan view of one of the removable sections; Fig. 3 is a longitudinal section on the line 3—3, 45 in Fig. 2; Fig. 4 is a transverse section on the line 4—4 in Fig. 2, and Fig. 5 is a perspective view from below of a modified form of section.

In Fig. 1 I have shown a boiler 1 of the 50 usual horizontal type which is covered with a suitable jacket of refractory material, such as asbestos or fire-brick. It is desirable that

the central portion of the end of the boiler and certain portions of the sides of the exposed part be accessible for inspection. Extending around the boiler are shown a number of iron straps 2, disposed at equidistant intervals, thus forming panels or sections along the sides of the boiler. The endmost section is where the removable covering will 60 preferably be used, since it is desirable at this point to inspect the rivets in the head of the boiler.

The removable sections which are used for the above purpose consist of an open framework 3, within which are disposed transversely extending and parallel refractory members 15, such as fire-brick of a suitable quality, which are then held in place by two or more longitudinally extending straps 70 or metal strips 4. Extending longitudinally across the outer side of each section are other straps or reinforcing members 5 formed at their ends into eyelets 7, which cooperate with other eyelets formed on the 75 next adjacent sections to constitute eyes through which bolts 8 may be passed to hinge these sections together.

On the end of the boiler a similar construction is used except that each section is 80 formed flat instead of being curved, and, if desired, the sections are held in place by reinforcing strips 11 which extend from the ends of the section to which they are attached.

A modified construction is shown in Fig. 5 where the framework 20 in which the refractory material is placed is provided across its bottom with a lacing 21 of wire, which takes the place of the straps shown 90 in the preceding figures, for the purpose of holding the brick in place.

It is not, of course, new to employ a removable covering on a boiler, but the present invention is directed to the provision of 95 a covering which shall be removable in conveniently handled sections, which are, however, securely fastened together and maintained in place when once put in position.

Other modes of applying the principle of 100 my invention may be employed instead of the one explained, change being made as regards the mechanism herein disclosed, provided the means stated by the following

claim or the equivalent of such stated means be employed.

I, therefore, particularly point out and distinctly claim as my invention:

5 In a boiler covering, a removable section comprising a shallow open frame work, refractory material laid therein, and a wire lacing extending across the open face of

such frame work, said lacing being adapted to maintain such material in position.

Signed by me, this 14 day of Sept., 1916.

JAMES C. WORKMAN.
